DESIGN FOR A COMBINED HOLDER FOR DRINKING GLASSES, DISHES, AND THE LIKEJohn Weber, Jr., Chicago, Ill., assignor to Walgreen Co., Chicago, Ill., a corporation of Illinois

Application January 5, 1946, Serial No. 125,317

Term of patent 14 years

(Cl. D44—10)

To all whom it may concern:

Be it known that I, John Weber, Jr., a citizen of the United States and a resident of Chicago, county of Cook, and State of Illinois, have invented a new, original, and ornamental Design for a Combined Holder for Drinking Glasses, Dishes, and the like, of which the following is a specification, reference being had to the accompanying drawing, forming part thereof.

In the drawing:

Figure 1 is a front elevational view of the combined holder for drinking glasses, dishes and the like, showing my new design, in a position to receive a glass;

The dotted line showing of the glass and the dish in Figures 1 and 3, respectively, is for illustrative purposes only.

I claim:

The ornamental design for a combined holder for drinking glasses, dishes, and the like, substantially as shown and described.

JOHN WEBER, JR.
